SELF-PROPELLED MARINE ANCHOR

Lynn G. Howell, Houston, Tex., assignor, by mesne assignments, to Standard Oil Development Company, Elizabeth, N. J., a corporation of Delaware

Application April 11, 1947, Serial No. 740,792

2 Claims. (Cl. 114—0.5)

1

The present invention is directed to an apparatus for anchoring ships or other watercraft. More particularly, the invention is concerned with an apparatus for anchoring ships or other watercraft which apparatus is propelled from a remote point and is raised by remote control.

In operating ships or other watercraft, particularly those employed in subsea prospecting for minerals such as petroleum, it is sometimes necessary to set up a number of stations on the water covering the area under prospection. A great portion of time is now required to occupy, for example, a station at which gravity determinations are to be made by virtue of the fact that each time a determination is made it is necessary to anchor the ship from which the reading is obtained. The conventional procedure requires the use of some sort of small auxiliary boat and one man or more. The small boat is employed to carry the conventional marine anchor a sufficient distance from the larger ship before releasing it so that the larger ship will be securely anchored. The distance required for anchoring a ship from which prospecting is taking place is primarily a function of the depth of the water, the deeper the water, the greater the distance. For example, for depths of about 100 feet it may be necessary to carry an anchor some 600 feet away before dropping it. It will be understood that each ship from which prospecting takes place often requires two anchors, one at the bow and one at the stern. It can be understood that considerable time may be consumed in establishing such a station. The problem is aggravated moreover, when lateral anchors are used which frequently is necessary when the wave motion is such that the ship requires stabilization by putting out more than two anchors. It will be apparent from the foregoing discussion that a considerable amount of time and effort could be saved if some faster and more convenient anchoring devices could be employed.

It is, therefore, the main object of the present invention to provide a variable buoyancy anchor which includes a propulsion device and which can be remotely controlled from the ship to be anchored.

It is also an object of the present invention to provide a rapid and efficient apparatus for anchoring seagoing ships or other watercraft.

The device of the present invention may be described briefly as comprising a stable variable buoyancy vessel which includes one or more anchor flukes and propulsion means.

More specifically, the device of the present in-

2

vention may be described as involving a vessel of suitable size and shape for buoyancy, a stabilizing means forming an integral part of the vessel and one or more anchor flukes suitably attached to the vessel. The device of the present invention also includes means for propulsion and for sinking and raising the vessel, including the anchor fluke.

The invention will now be further described in conjunction with the drawing, in which

Fig. 1 illustrates one embodiment thereof; and Fig. 2 is a cross section taken along the lines II—II of Fig. 1.

Referring now to the drawing, numeral 11 designates a vessel of a general streamlined shape adapted to be propelled easily through water. Vessel 11 has attached to it and forming an integral part thereof a keel or stabilizing means 12 rigidly fixed to the buoyant vessel 11. Vessel 11 may be suitably divided into three compartments 13, 14 and 15, compartments 13 and 15 being sealed off from compartment 14 and forming buoyancy and air compartments. Compartment 14 is in communication with an air motor 16 through a conduit 17. Air motor 16 is rigidly attached to the vessel 11 by suitable means and is provided with a propeller or screw 18 which when actuated by introduction of the air or other suitable compressed gas through conduit 19 forms a means for propelling the buoyant vessel 11 which may be both propelled and controlled by the introduction of air. The air thus serves as a means for propelling the vessel 11 and provides buoyancy as described. The stabilizing means or keel 12 is so constructed that a portion of the stabilizing means 12 indicated by the numeral 20 serves as a rudder for the device. The rudder 20 may or may not be rigidly arranged with the keel 12. If desired, the rudder 20 may be arranged to allow setting or controlling the direction of travel of the anchor of the present invention other than in a straight line.

Affixed to the rudder 20 is a cable 21 which connects with and is fixed to a ship or other watercraft not shown.

The keel or stabilizing device 12 has affixed to it an anchor fluke 22 which may be affixed rigidly or flexibly to the keel 12.

In employing the device of the present invention the vessel 11 is placed in the water alongside the afore-mentioned ship, which is to be anchored at a given spot. The cable 21 is affixed to the ship, on a suitable reel for easy manipulation. The air conduit or hose 19 is also flexibly connected to the ship and wound on a

suitable reel or paying out device. Air is injected into motor 16 under a pressure of about 5 pounds to give buoyancy to the vessel 11. When it is desired to send the vessel 11 out to a certain distance from the ship air pressure up to about 100 pounds is employed to cause the air motor 16 to be operative and to provide buoyancy by maintaining the chamber 14 filled with air and prevent water entering into the chamber 14 through an orifice or opening 23. Under these conditions the air motor 16 causes the propeller screw 18 to rotate and propel the vessel 11 away from the ship which is to be anchored, the excess air bubbling outward from the compartment 14 through opening 23. The vessel 11 is so designed that it will remain in a floating condition and about half submerged when it is traveling on the surface of the water.

When the cable 21 has been let out to a sufficient distance, the flow of air through air conduit 19 is stopped and, by suitable valving arrangement, air is vented and water enters the compartment 14 through opening 23 allowing the whole assembly to be submerged and sink to the floor of the sea. As the vessel 11 sinks to the floor of the sea the anchor fluke 22 engages with the mud and firmly affixes itself to the bottom of the sea allowing the ship, not shown, to be anchored. The fluke 22 may be firmly fixed in the mud by the ship exerting tension on the cable 21.

Ingress of water to the motor 16 through conduit 17 is prevented by the float valve arrangement located in chamber 24 affixed to the top of the vessel 11. The float valve arrangement is of conventional type and is indicated by the numeral 25 and is actuated by float 26 which prevents the water from entering into the conduit 17. As the level of the water in vessel 14 rises to a point determined, automatically the valve 25 is closed and water is prevented from entering into the conduit 17 and thus into the motor 16.

When it is desired to lift anchor, air is forced from a supply of air on the ship, not shown, through the inlet line 19 sufficient to give buoyancy to the vessel 11 by forcing water from compartment 14, tension on the cable 21 having been slackened off. As mentioned before, approximately 5 pounds of air will usually be sufficient to give buoyancy to the vessel 11 at the surface but the amount of air pressure required will vary depending on the depth to which the vessel 11 has been submerged. Suffice to say a sufficient air pressure will be employed to free completely compartment 14 of water. The buoyancy thus given to the vessel 11 will cause the anchor fluke 22 to be freed from the muck and mud at the bottom of the sea. After the vessel 11 has been raised to the surface it may be returned to the ship by reeling in the cable 21 or by allowing the ship to proceed to the point where the anchor rests while reeling up the cable 21 and air conduit 19.

When employing a pressure of about 5 pounds per square inch to give buoyancy to the device of the present invention, as mentioned before, about 100 pounds per square inch, are necessary for propulsion. Under these conditions the device of the present invention will travel from the ship to be anchored at a rate of 100 to 150 feet per minute.

As mentioned before, the size and dimensions of the device of the present invention will vary

with the size of the ship or other watercraft to be anchored. For a boat 65 feet in length the vessel 11 should have a displacement of about 4 cubic feet.

5 While the fluke 22 has been shown rigidly affixed to the keel 12, it will be apparent to workers in the art that the fluke 22, or a plurality of such flukes, may be secured to the underside of vessel 11 in a manner such that they may be readily adjusted to any desired angle for effective engagement into the floor of the body of water. Such a modification is within the spirit and scope of the present invention.

15 The type of flukes employed in the present invention will be those anchor flukes generally available in the art. As examples, the Danforth anchor fluke and the Northill fluke are suitable in the apparatus of the present invention. As shown, the vessel 11 may be made in several 20 compartments. It may be desirable under some conditions, however, to make the vessel 11 of a single compartment. Sometimes, however, it will be desirable to compartmentalize the vessel 11 to give stability to the device.

25 While the apparatus of the present invention has been shown to be of an elongated barrel shape with the ends streamlined to navigate water, the vessel 11 may be of any shape which 30 is buoyant and which is provided with stabilizing means to maintain the assembly upright in water. For example, the compartments 13, 14 and 15 may be contained in a spherical shape or may be contained in an ovoidal vessel. The 35 shape of the vessel 11 may influence the stability and the water drag of the device but otherwise has little to do with its success.

40 While the device of the present invention has been illustrated as being propelled by the air motor 16 with the attached propeller screw 18, it will be apparent to the skilled worker that the air employed for buoyancy may be the propulsion means without employing an air motor. For 45 example, it may be desirable under some conditions to eliminate the air motor 16 and the propeller screw 18 and to provide an air jet adjacent the rudder device 20. Under these conditions the air conduit 19 connects into the vessel 11 at the point the air conduit 17 enters the 50 valve chamber 24. When the air jet is employed as the propulsion means air pressure is introduced through the air conduit into the top of the vessel 11 sufficient to eject the air as a jet from the stern of the vessel and propel it rapidly 55 through the water.

60 The device of the present invention has been described and illustrated by anchor flukes forming an integral part thereof. The invention may have substituted for the anchor flukes suitable grappling means which are sunk into the muck and mud on the sea bottom and cause the device to be firmly anchored. Similarly, the grappling means may be hooks or other similar equipment which will allow objects to be retrieved.

65 When the anchor flukes of the present device are substituted for by grappling means it may be possible to employ the present invention in raising objects from the sea floor. For example, a small object is located below the surface of the sea. The buoyant vessel of the present invention including a suitable grappling mechanism may be sunk above it and the grappling device engaged with the object and the buoyant vessel then raised by blowing out the water from

the compartment 14 by application of suitable air pressure.

While grappling means have been differentiated from anchor flukes in the above discussion, it is intended that the terminology "grappling means" will encompass any device engageable with the mud and/or muck on the sea bottom or with objects which may be lifted from the floor of the sea.

The nature and objects of the present invention having been completely described and illustrated, what I wish to claim as new and useful and to secure by Letters Patent is:

1. A self-propelled, variable-buoyancy anchor comprising, in combination, a hollow vessel defining an orifice in the underside thereof, said orifice providing free flow of fluid into and out of the interior of the vessel, means for passing compressed gas into the top of said vessel and for venting said gas as desired, said means including a conduit of suitable length for connection between the vessel and a source of compressed gas arranged upon a watercraft which is to be anchored, propelling means responsive to flow of said gas therethrough for propelling the vessel in floating condition, means carried by the vessel for stabilizing the direction of propulsion thereof, and grappling means affixed beneath the vessel.

2. A self-propelled, variable-buoyancy device for anchoring a watercraft comprising, in combination, a hollow vessel defining an open orifice in the underside thereof, a compressed air motor secured to the underside of said vessel, a propeller carried and driven by said motor for propelling

the vessel in floating condition, a first conduit of suitable length having one end connected to an air inlet of said motor and another end adapted to be connected to a source of compressed air on said watercraft, a second conduit for transferring air from an air outlet of said motor into the top of said vessel whereby introduction of compressed air into said conduits and said motor causes water to be expelled from the vessel through said orifice and causes the vessel to be propelled, and venting of air from the conduits and motor permits water to flood the vessel through the orifice, means carried by the vessel for stabilizing the direction of propulsion thereof, and at least one anchor fluke affixed beneath said vessel.
